UNITED STATES PATENT OFFICE.

THOMAS MANDEVILLE HOPPER, OF SUFFERN, NEW YORK, ASSIGNOR TO RAMAPO IRON WORKS, OF HILLBURN, NEW YORK, A CORPORATION OF NEW YORK.

RAILWAY-FROG.

No. 926,488.

Specification of Letters Patent.

Patented June 29, 1909.

Application filed March 5, 1909. Serial No. 481,333.

To all whom it may concern:

Be it known that I, THOMAS MANDEVILLE HOPPER, a citizen of the United States, residing at Suffern, in the county of Rockland, 5 State of New York, have invented certain new and useful Improvements in Railway-Frogs, of which the following is a specification, reference being had to the accompanying drawings, forming a part hereof.

10 My invention relates particularly to means for securely holding the parts of a railway frog in their proper positions with relation to each other, and the invention consists in the new and novel features of construction in 15 combinations of parts hereinafter set forth and claimed.

Figure 1 is a plan view of a railway frog embodying my invention. Fig. 2 is a side elevation showing one form of holding means. Fig. 3 is a cross section on the line 20 3—3 of Fig. 1.

The frog comprises the main rails A, the wing rails B and the frog block C in the usual manner. These parts may be of any preferred material and of any desired section, 25 although my invention will be found of special value in connection with frog blocks of a tough or hard material such as manganese steel.

30 In order to securely hold the parts of the frog together and in their proper relative positions the frog block C is provided with one or more arms or projections d formed integral therewith. Preferably these arms or 35 projections are circular in section, although they may be of any desired section, and are preferably formed in pairs on opposite sides of the frog block substantially at right angles to the center line thereof, such pairs being 40 provided at suitable distances apart throughout the length of the block. The webs of the adjacent wing and main rails together with the strap or reinforcing bar e, if any be used, are formed with corresponding openings or passages f through which the arms or 45 projections d extend. At or near their outer ends the arms or projections are provided with perforations d' to receive wedge keys, beveled cotter pins or any other suitable

means g for wedging and securely holding 50 the parts together in proper position.

By this construction the number of parts in a frog block is greatly reduced. Instead of bolts the parts are held together by projections which are integral with the block 55 itself and which permit keys or cotters to be used instead of nuts or nut locks. Greater safety results and the liability of the parts of the frog working apart is reduced to a minimum. The parts of the frog are readily and 60 quickly assembled and in case of wear or injury the damaged part can be easily removed and replaced.

Although I have shown my invention embodied in one particular kind of frog it is obvious that the invention may be employed in connection with any of the well known types of frogs now in use. It is obvious also that various changes may be made in the details of the construction herein shown and 65 described which changes are within the limits of mechanical skill and which may be made without departing from the invention provided the means set forth in the following 70 claims be employed.

I claim as my invention:

1. In a railway frog, the combination with a track rail provided with an opening therethrough, of a frog block provided with a projection formed integral therewith and arranged substantially at right angles to the center line of the block and projecting through said opening, and means removably secured at or near the end of said projection to engage with the parts of the frog adjacent 85 to said frog block.

2. In a railway frog, a frog block provided with a projection formed integral therewith and having a perforation near its end, and a wedge key removably secured in said perforation and adapted to engage with the parts of the frog adjacent to said frog block.

3. In a railway frog, the combination with a track rail provided with a plurality of openings in its web, of a frog block provided with a plurality of projections formed in pairs opposite each other and extending through said openings, and means removably

secured at or near the end of each of said projections to engage with the parts of the frog adjacent to said frog block.

4. In a railway frog, the combination with the main and wing rails having openings formed in the webs thereof, of a frog block provided with a plurality of projections passing through the openings provided in said rails, and wedge keys engaging said projec-

tions to wedge the parts together and hold the same against displacement, substantially as described.

This specification signed and witnessed this 26th day of February, A. D., 1909.

THOMAS MANDEVILLE HOPPER.

Signed in the presence of—

JAMES BOORMAN STRONG,

LA VERNE EDWARD TRAVERS.
